T. T. KING

SWIVEL MANDREL

Filed May 12, 1924

UNITED STATES PATENT OFFICE.

THEODORE T. KING, OF OKLAHOMA CITY, OKLAHOMA, ASSIGNOR, BY DIRECT AND MESNE ASSIGNMENTS, OF THREE-FOURTHS TO J. M. WATSON, OF OKLAHOMA CITY, OKLAHOMA, AND ONE-FOURTH TO F. B. OWEN.

SWIVEL MANDREL.

Application filed May 12, 1924. Serial No. 712,877.

To all whom it may concern:

Be it known that I, THEODORE T. KING, a citizen of the United States, residing at Oklahoma City, in the county of Oklahoma and State of Oklahoma, have invented certain new and useful Improvements in Swivel Mandrels, of which the following is a specification.

This invention relates to a swivel mandrel, and particularly to a construction in which the cable securing member is contained within a socket body and the parts are capable of relative rotary movement as usual in oil well or other drilling.

In devices of this character the cable is secured to the swivel member by embedding its lower end in a body of fusible metal and it is necessary to heat this member when it is desired to remove and replace the cable connection for any reason. In prior constructions this heating affects the temper and diameter of the mandrel causing the parts to bind and unevenly wear the socket, and also preventing the desired impact action.

If the cable securing connection be detached or separately movable from the mandrel member an undesirable hammering between the parts results.

This invention has for an object to provide a novel and improved construction wherein a mandrel and cable securing connection are detachably interlocked so that they may be separated for heating purposes and the mandrel always retained at its original fit and temper while the interlocked connection prevents hammering of the members upon each other as they move as a unit, thus insuring an even wear of the socket bore.

Another object of the invention is to provide an improved connection between the cable securing member and the mandrel member comprising a bayonet slot and pin, together with means for locking the pin in its secured position when the parts are assembled so as to prevent any relative movement and present a smooth continuous operating face for contact with the bore of the socket.

Other and further objects and advantages of the invention will be hereinafter set forth and the novel features thereof defined by the appended claims.

In the drawing:

Figure 1 is an elevation of the invention; Figure 2 is a section on line 2—2 of Figure 1;

Figure 3 is a vertical section showing the mandrel assembled in its socket; and

Figure 4 is a section on line 4—4 of Figure 1.

Like numerals refer to like parts throughout the several figures of the drawing.

The numeral 10 designates a socket or body of any desired size or configuration having an interior bore 11 within which the mandrel member 12 is mounted for reciprocatory and rotary movement. This socket is provided at its lower end with the usual threaded opening 13 for the reception of the tool and with an exteriorly threaded connection 14 at its upper portion 15. This portion is formed with a bore 16 of substantially the diameter of the operating cable 17 which passes therethrough and is secured to the block member 18 which is of similar diameter to the mandrel 12 and closely fits the interior of the socket bore 11. The cable 17 is secured to the block 18 in any desired manner, preferably by the use of a fusible Babbitt metal inserted in the enlarged recess 19 to surround and imbed the lower end of the cable forming a rigid connection with the block for the operation of the tool.

The block 18 is detachably interlocked with the mandrel 12 so as to move as a unit therewith, and a preferred form of such connection comprises a pin 20 carried by the neck 21 from the securing block 18 and adapted to seat in a socket 22 formed in the wall of the mandrel member 12. This wall is also formed with an elongated slot 23 through which the pin passes when the parts are assembled until it reaches its locking position at the socket 22. The parts being thus interlocked it is desirable to prevent any accidental disconnection during the operation of the tool and for this purpose a latch bar 24 is disposed in the slot 23 and pivotally mounted at its upper end by means of a cross pin 25 so as to swing outwardly from the slot as shown by dotted lines in Figure 2, and to lie flush with the outer wall of the mandrel when in closed position.

This bar may be provided with a recess or socket 26 at its lower portion for the purpose of engaging the same when it is desired to disconnect the members of the mandrel.

In the operation of the tool the parts are assembled as before described and the mandrel with the cable securing member operate as a unit having a swivel movement within the socket as usual in this class of tools. When it is desired to remove or change the cable connection the securing member is withdrawn from its interlocked connection with the mandrel by turning the pin into alignment with the slot and directly separating the parts. The securing block may thus be heated to remove or replace the cable connection without in any wise affecting the temper or diameter of the mandrel member as it is important to maintain the proper fit of this member in order to prevent an uneven wear of the bore of the socket and maintain a free swiveling movement of the tool under all conditions of use.

It has also been found important to positively interlock the cable securing block with the mandrel in order to prevent any relative movement or hammering of these parts upon each other which tends to affect their fit within the socket by producing an increased diameter at the points of contact. This is effectually accomplished by the use of the interlocked connection between the neck of the securing block and the mandrel, together with the retaining latch by which the bayonet slot and pin are secured in interlocked position.

While the specific construction of the interlocked connection has been shown and described, the invention is not confined thereto as it is obvious that changes and alterations may be made without departing from the spirit of the invention as recited by the following claims.

Having thus described my invention, what I claim as new and desire to secure by Letters Patent is:

1. In a tool of the class described, a socket, a swivel member disposed therein, and a cable securing member said members being formed with a detachable interlock-

ing connection to permit withdrawal of the cable member from said swivel member.

2. In a tool of the class described, a socket, a swivel member disposed therein, and a cable securing member detachably interlocked with said swivel member by a bayonet slot and pin connection therewith.

3. In a tool of the class described, a socket, a swivel member disposed therein, a cable securing member detachably interlocked with said swivel member, and a locking member mounted upon the swivel to prevent movement of said connection in operation.

4. A swivel mandrel provided with a recess therein, a securing block having a neck adapted to enter said recess, and an interlocked connection between said neck and the walls of said recess.

5. A swivel mandrel provided with a recess therein, a securing block having a neck adapted to enter said recess, and a pin projecting from said neck and adapted to be immovably retained by a seat in the wall of said recess.

6. A swivel mandrel provided with a recess therein, a securing block having a neck adapted to enter said recess, a pin projecting from said neck and adapted to be immovably retained by a seat in the wall of said recess, and a latch bar mounted upon said wall and adapted to retain said pin within said seat.

7. In a swivel mandrel, a body member provided with a recess having in its outer wall an elongated slot and lateral seat, a cable securing block provided with a neck entering said recess, and a pin upon said neck adapted to traverse said slot and enter said seat.

8. In a swivel mandrel, a body member provided with a recess having in its outer wall an elongated slot and lateral seat, a cable securing block provided with a neck entering said recess, a pin upon said neck adapted to traverse said slot and enter said seat, and a retaining bar pivotally mounted at the upper portion of said slot and adapted to substantially fill the same when in closed position.

In testimony whereof I affix my signature.
THEODORE T. KING.
